ABSTRACT OF THE DISCLOSURE

A golf club having a head with a ball contacting face and a pair of twin shafts extending upwardly from the head. An enlarged grip assembly maintains the shafts in spaced relation, and with the shaft mounting at the club head, tends to prevent twisting of the club face in the swing arc. Vibration damping material is placed between the shafts.

This invention relates to golf clubs, and more particularly to a golf club having a ball contacting face so related to the grip assembly as to have more complete control over the club face as it is moved in its swing arc.

There are all sorts and sizes of golf clubs presently available for the golfer to choose from, each of which is a different shape and has different advantages and disadvantages. The selection of a club is dependent entirely upon the likes and dislikes of the user. There are, however, certain common problems with many golf club structures regardless of their shape or size, such problems being inherent in their design and in the manner in which a golf club is normally used by a golfer. A typical example is in putter constructions, wherein all putters are provided with a ball contacting face of considerable length relative to the diameter of the ball.

The usually desirable putting swing is to have the face of the club travel in an arc in a plane normal to the desired direction of ball travel. The club face should always be in a position normal to the desired direction. However, the usual putting stance and swing can cause a twisting of the club face during the swing unless great care is exercised by the golfer in striking the ball. Such twist occurs because of the motion of the club head as it is brought back by the golfer, the twist normally not being compensated for, and the ball is caused to travel in an unwanted path following the impact. Additionally, the excessive length of the club face relative to the diameter of the ball can cause the ball to go off in the wrong direction if, as often occurs, the ball is struck near the toe of the club head, such being easily possible with presently designed golf clubs.

The device in which this invention is embodied comprises, generally, a golf club including a head having a ball contacting face of any suitable dimension, and a pair of upwardly extending and spaced shafts. At the upper end of the twin shafts is a broad handle assembly for holding and swinging the club.

Such a club provides more accurate control of the club face relative to the ball, both during the swing of the club head and during the instant of impact with the ball, to avoid the twisting or turning problem of the club face relative to the ball. The twin shaft arrangement and the broad grip structure combine to provide a more accurate "feel" as the club is used, and thus better control of the club face as it approaches the ball. At the same time, the twin shaft and broad grip combination prevents the problem of club twist at the moment of impact, regardless of where the point of contact of the ball with the club face occurs. These and other advantages will become more apparent from the following description and drawing in which:

2

FIG. 1 is an elevational view of a golf club embodying the invention.

FIG. 2 is a side elevational view of the golf club illustrated in FIG. 1, with parts broken away and in section.

FIG. 3 is a plan view of the golf club illustrated in FIGS. 1 and 2, taken substantially along the line 3—3 of FIG. 1 and looking in the direction of the arrows.

FIG. 4 is a cross sectional view of the grip structure of the club illustrated in FIGS. 1—3, taken substantially along the line 4—4 of FIG. 2 and looking in the direction of the arrows.

Referring more particularly to the drawing, FIGS. 1 and 2 best illustrate the overall golf club construction. It is to be understood from the outset that the inventive concept relates to all golf clubs, whether woods or irons and whether shallow or steep faces. For convenience, the following description and drawing are related to a putter.

The golf club illustrated in the drawing includes a head, indicated generally by the numeral 10, the head 20 having a ball contacting face 12 and sufficient weight therebehind to properly balance the club and to provide the required amount of impact force. Head 10 includes a bottom surface 14 merging into arcuate surfaces 16 and 18, the surface 18 merging into the face 12. Arcuate surfaces 16 and 18 are provided to prevent the head from scuffing the grass or ground, indicated by dashed and dotted lines 20, in either the back swing or fore swing.

Extending upwardly and outwardly over the club face 12 is a gooseneck portion 22, integrally formed from the 30 club head 10. Extending upwardly from the gooseneck 22 and from the club head 10 is the handle assembly, indicated generally by the numeral 24. Handle assembly 24 includes two shafts 26 and 28, shaft 28 being secured to the upper portion of the gooseneck 22 and shaft 26 being 35 secured in the head 10 at a point spaced from the connection of the shaft 28.

Shafts 26 and 28 may be tubular in construction and secured to the gooseneck 22 and club head 10 in any suitable fashion. For convenience it is shown that shaft 40 28 is secured to the gooseneck 22 by means of a pin 30, suitably received in a cylindrical opening 32 in the gooseneck 22, and extending upwardly into the tubular shaft 28 for anchoring purposes. Similarly, shaft 26 is a tubular member and is secured in the club head 10 by 45 means of a pin or shaft 34 suitably received in a cylindrical aperture 36 in the head 10. Pin 34 extends upwardly within the shaft 26 for anchoring purposes.

At the upper ends of the twin shafts 26 and 28 is the grip assembly, indicated generally by the numeral 38. 50 Grip assembly 38 includes a handle member 40 of any suitable material. The handle member 40 extending between the twin shafts 26 and 28, is best illustrated in FIG. 4. Such construction maintains the relative location of the two shafts and at the same time provides a 55 broad grip surface at both the front and back of the club for ease and comfort of the user. A cap member 42 is suitably secured on the ends of the shaft 26 and 28 and the upper end of the handle member 40.

It is preferred that the gooseneck 22 and its upwardly 60 extending shaft 28 be so disposed relative to the club face 12 that the plane containing the impact point of the club head with the ball falls between the shafts 26 and 28. Thus, the twin shaft and grip assembly give the user the feel of striking the ball directly in alignment with 65 his hands, or with a guiding finger thus providing better control over the impact of the club face 12 with the ball 44. To accomplish this it is necessary that the shafts 26 and 28 be effectively joined to the club head 10 at spaced points or locations. While the assembly is shown in the drawing to include twin shafts 26 and 28 in alignment in a plane normal to the plane of the face 12, they could 70

also be so disposed such that the twin shafts 26 and 28 join the head 10 at points spaced both laterally or normal to the club face 12, and longitudinally of the head 10. It is desirable that at the grip portion 28 the two shafts be parallel and properly aligned.

In order to avoid transmission of any objectional vibrations, or relative vibrations, in the twin shafts 26 and 28 as a result of the head 10 striking the ball, vibration damper 46 may be provided between the shafts 26 and 28. Damper 46 may take any suitable form and is shown for convenience to be a small block of rubber mounted between the shafts 26 and 28 at points upwardly spaced from the head 10.

Thus, a golf club construction is provided which is extremely sensitive to the feel of the golfer and which eliminates the twisting or torquing problems normally found in the club face as it travels through its arc. By controlling the amount of twist of the club head, the golfer is assured of more accuracy in the travel of the ball.

While numerous changes and modifications will occur to those having skill in the art, after having had reference to the foregoing description and drawing, it is not intended to limit the scope of the invention by the foregoing but by the scope of the appended claims in which:

The embodiments of the invention in which an exclusive property or privilege is claimed are defined as follows:

1. A golf club adapted to strike a ball and comprising:
a head having a face thereon adapted to contact said ball;
a first shaft extending upwardly from said head;
a second shaft extending upwardly from said head and being spaced from said first shaft and on the opposite side of the plane containing said face from said first shaft;
grip means surrounding and joining the upper ends of said first and second shafts;
and vibration damping means between said first and second shafts for damping vibrations therein.
2. A golf club adapted to move a ball in a desired direction and comprising:
a head having a ball contacting face thereon;
a first shaft extending upwardly from said head;
a second shaft extending upwardly from said head in generally spaced parallel relation to said first shaft and having a portion adjacent said head extending outwardly over said face;
said face being located in a plane generally normal to said desired direction and between the plane con-

taining the axis of said first shaft that is generally normal to said desired direction and the plane containing the axis of said second shaft that is generally normal to said desired direction; and

5 a grip member having a portion extending between said shafts to secure said shafts in spaced relation.

3. The golf club set forth in claim 2 and further including vibration damping means between said first and second shafts for damping vibrations therein.

4. A golf club adapted to strike a ball and comprising:
a head having a ball contacting face thereon and a shaft receiving portion extending upwardly and outwardly over said face;

10 a first shaft secured in said portion in said head and extending upwardly therefrom;

15 a second shaft secured in said head at a point spaced from said portion of said head and extending upwardly therefrom and on the opposite side of the plane containing said face from said first shaft, said second shaft terminating in spaced parallel relation to said first shaft;

20 a grip member extending longitudinally of the upper portions of said first and second shafts and having a portion disposed therebetween, said grip member and said first and second shafts forming a handle; and

25 a cap member receivable in the ends of said first and second shafts.

5. The golf club set forth in claim 4 and further including a vibration damper disposed between said first and second shafts and upwardly spaced from said head.
